(57) **CLAIM**

The ornamental design for a hand held illumination device for phototherapy, as shown and described.

DESCRIPTION

FIG. 1 is a perspective view from the front, right side of a hand held illumination device for phototherapy according to the design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

Throughout the Figures, where shown, the dashed lines are included for the purpose of illustrating portions of the article which form no part of the claimed design.

1 Claim, 7 Drawing Sheets
